LEO P. KEVENEY AND CARL F. COLLINGE, OF TOLEDO, OHIO.

BINDER.

1,135,697.

Specification of Letters Patent.

Patented Apr. 13, 1915.

Application filed November 8, 1913. Serial No. 799,881.

To all whom it may concern:

Be it known that we, LEO P. KEVENEY and CARL F. COLLINGE, citizens of the United States, and residents of Toledo, in the county of Lucas and State of Ohio, have invented a certain new and useful Binder; and we do hereby declare the following to be a full, clear, and exact description of the invention, such as will enable others skilled in the art 10 to which it appertains to make and use the same, reference being had to the accompanying drawings, and to the characters of reference marked thereon, which form a part of this specification.

15 Our invention relates to binders for bundles.

It has for its object to produce a binder which will draw the parts forming the bundle tightly together and then lock the ends 20 of the binder.

It also has for its object to provide a wide binder to prevent the parts of the bundle from working laterally and out of the binder.

25 It has for its further object to provide a binder which will tightly inclose or secure a bundle of any size within the limits of the binder.

In the construction containing the invention, an engaging means is secured to one 30 end of the binder and is adapted to engage with an intermediate part or the other end of the binder, and means is provided for drawing the engaging means and the part 35 with which it is engaged toward the end to which it is secured and locking it in position.

The invention may be contained in many 40 different constructions. We have illustrated one of such constructions and shall describe it hereinafter to show how such constructions may be made and operated.

Referring to the drawings, Figure 1 illustrates the application of the invention and shows the binder locked in position. Fig. 2 45 is a top view of a portion of the binder, and Fig. 3 illustrates an end view of the end portion of the clasp shown in Fig. 2.

1, Fig. 1, is a binder chain formed of broad links 2. Each link is of wire bent to 50 form three sides of a square or a rectangle and having the sides 3, the ends or cross-bars 4 and eyes 5 which are bent over and pivot transversely to the end portions of the preceding link. The first link is secured to 55 the clasp 10 formed of wire of more or less elasticity and having elastic sides 11 which

are brought together and turned about each other to form interengaging loops 12 and terminate in horns 13 which slant upward and outward. The sides 11, as shown in Fig. 60 3, are provided with eyes 14 which may be formed by a complete short turn in the wire. When thus formed a certain amount of elastic play is given to the free end of the clasp. A wide engaging hook 15 is pivotally 65 secured in the eyes 14. The hook 15 is formed of wire having end portions 16 which extend into the eyes 14 and are permanently secured therein, side portions 17 which are bent away from the free end of 70 the clasp into hooks 18 and the cross-bar or end portion 19.

In the operation of the binder and clasp, the chain is placed about a bundle and the ends of the chain are brought as near as 75 possible together or made to overlap or the free end may be turned back along the chain, on the inside or on the outside, preferably on the inside. The cross-bar portion 4 of the farthest of the links possible is 80 caught by the hook 15. The free end of the clasp then lies to the back or the outside of the hook. The free end of the clasp is tilted away from the hook, turning in the eyes 5 of the link of the chain secured there- 85 to, pulling the hook with it and the cross-bar 4 of the link caught thereby, double the length of the distance between the pivot line or turning axes of the clasp on the end of the chain and of the hook in clasp, that is, 90

double the distance between the eyes 5 of the first link of the chain and the eyes 14 in which the hooks are pivoted. The hook is of such length relative to the member 11 to which it is pivotally connected, that the 95 lip of the hook 15, swings into close fitting contact with the cross bar 10 forming a part of the clasp member 11, as shown in Fig. 1. The hook thus incloses the cross bar of the link which it engages between itself and the 100 clasp member. This prevents the link from becoming disengaged from the hook when the bundle is thrown or jarred from any reason whatever. If the link with which the hook is connected slips forward in the 105 direction of the clasp member, which may be caused by jarring of the bundle, it will not be released from the hook as it will slip over the lip of the hook and be reengaged by the hook. As the clasp is pressed down 110 to the bundle its sides 11 may be pressed together and the horns locked under the sides

3 of any one of the links, it may be the second or the third link of the chain from the clasp. The hook 15 tends to pull the clasp up or away from the bundle so that the 5 horns remain locked beneath the sides of the link with which they engage. The clasp may also be so made that a light pressure is required to bend it into engaging position. The horns 13 being inclined upward and 10 outward will slip down between the sides 3 of the link with which they engage and lock therewith, so that the ends of the chain will be secured by mere pressure on the free end of the clasp when it has been drawn over 15 to near engaging position.

The construction described may be greatly varied by those skilled in the art without in anywise departing from the spirit of the invention.

20 Having thus described our invention, what we claim as new, and desire to secure by Letters Patent, is,—

25 1. The combination of a chain having rectangular wire links, each link having an end cross-bar, a clasp secured to one end of the chain and having a rectangular hook for en-

gaging any one of the cross-bars of the links, the hook being connected to the central portion of the clasp, the clasp having elastic upwardly and outwardly turned side 30 members which engage with the side bars of one of the links by closing movements of the clasp.

2. The combination of a chain having rectangular wire links, each link having an end cross-bar, a clasp secured to one end of the chain, a rectangular hook pivoted centrally to the clasp for engaging any one of the cross-bars of the links, the hook having a downwardly and rearwardly turned lip extending to a point close to the cross-bar of the clasp when the binder is in binding position.

In testimony whereof, we have hereunto signed our names to this specification in the 45 presence of two subscribing witnesses.

LEO P. KEVENEY.
